CLAIM

The ornamental design for a soap dish or the like, as shown and described.

DESCRIPTION

FIG. 1 is a top, front, and right side perspective view of a soap dish or the like showing our new design, the broken-line disclosure of a portion of a wall being for illustrative purposes only and forming no part of the claimed design;

FIG. 2 is a top plan view thereof;

FIG. 3 is a front elevational view thereof;

FIG. 4 is a right side elevational view thereof;

FIG. 5 is a left side elevational view thereof;

FIG. 6 is a bottom plan view thereof; and,

FIG. 7 is a top plan view of an alternate embodiment thereof, the only difference being that it is a mirror image of the first embodiment.
